UNITED STATES PATENT OFFICE

2,427,098

VARIABLE ATTENUATOR FOR CENTIMETER WAVES

Eugene O. Keizer, Princeton, N. J., assignor to Radio Corporation of America, a corporation of Delaware

Application October 23, 1943, Serial No. 507,467

9 Claims. (Cl. 178—44)

1

This invention relates generally to microwave apparatus and more particularly to improved methods of and means for providing variable attenuation of microwaves in a waveguide transmission system.

It is well known in the art that considerable attenuation of microwaves is provided by constricting the walls of a microwave waveguide to a dimension less than one-half wavelength along the magnetic axis of wave propagation when the dielectric within the waveguide is air. For high dielectric constant materials the cut-off wavelength is increased in proportion to the value of the dielectric constant. The attenuation provided by such constricted waveguides increases rapidly as the transmitted wavelength is increased above the critical value. The instant invention utilizes this property of waveguide transmission systems by employing a section of waveguide having tapered portions for matching the constricted waveguide portion to adjacent sections of the waveguide having dimensions providing free transmission of said microwaves. Variable attenuation is provided in the constricted waveguide portion by employing therein a dielectric having a relatively high dielectric constant. The ratio of the portion of the constricted waveguide employing an air dielectric to that of the constricted waveguide having the high dielectric constant material determines the effective attenuation of the system. The portion of the constricted waveguide having the high dielectric constant material will provide a waveguide transmission path having low attenuation, since the effective cut-off wavelength of this portion of the waveguide will be above that of the transmitted energy. The resultant attenuation of the constricted waveguide portion may be dependent upon the volume of the high dielectric constant material which is inserted within the constricted portion of the waveguide.

One form of variable attenuator providing satisfactory attenuation adjustment comprises a waveguide having a constricted portion which encloses a tapered slug of high dielectric constant solid material which may be moved longitudinally along the guide by means of projections which extend through longitudinal slots in the guide faces. This embodiment of the invention may employ circular, elliptical or rectangular waveguides having all or predetermined opposite faces of the guide constricted, as desired.

Another embodiment of the invention which may be employed comprises a constricted waveguide portion which includes means for introducing therein a high dielectric constant liquid. The liquid may be introduced by any convenient hydraulic means to a desired depth within a limited length of the constricted waveguide portion, or the liquid may be inserted to provide a variable

2

length liquid dielectric path within a U-shaped portion of the constricted waveguide.

Among the objects of the invention are to provide an improved method of and means for attenuating microwave energy within a waveguide transmission system. Another object of the invention is to provide an improved method of and means for attenuating microwave energy within a waveguide transmission system by providing an adjustable length of constricted waveguide having cut-off frequency higher than the frequency of the energy to be transmitted. An additional object of the invention is to provide an improved method of and means for attenuating microwave energy in a waveguide transmission system wherein a low-loss high dielectric constant material may be adjustably introduced into a constricted portion of the waveguide transmission system whereby effective microwave transmission is accomplished through the high dielectric constant material while desired attenuation is provided by the constricted waveguide portion employing a low constant dielectric. Another object of the invention is to provide an improved method of and means for providing adjustable attenuation of microwave energy in a waveguide transmission system wherein a high dielectric constant low-loss liquid is introduced into a portion of a constricted waveguide section to lower the cut-off wavelength of said constricted guide portion. An additional object of the invention is to provide an improved adjustable attenuator for microwave energy having minimum wave reflection characteristics due to discontinuities therein.

The invention will be further described by reference to the accompanying drawings of which Figure 1 is a perspective view of one embodiment thereof, Figure 2 is a cross-sectional view of Figure 1 taken along the section line II—II, Figure 3 is a perspective view of a modification of the device shown in Figures 1 and 2, Figure 4 is a perspective view of a second embodiment of the invention, Figure 5 is a fragmentary cross-sectional view of Figure 4 taken along the section line V—V, and Figure 6 is a perspective view of a third embodiment of the invention. Similar reference characters are applied to similar elements throughout the drawing.

Referring to Figures 1 and 2, a waveguide 1, of rectangular cross-section, includes a constricted portion 3 coupled thereto by means of tapered portions 5. The narrow side walls of the constricted portion 3 include longitudinal slots 7. A slug 9, of low-loss material having a relatively high dielectric constant, is inserted within the constricted waveguide portion 3, and proportioned to have substantially the same cross-sectional dimensions as the constricted guide. The ends 11 of the high dielectric constant slug may be ta-

pered to minimize wave reflections from the ends of the slug in both directions along the main waveguide 1. Adjusting elements such as, for example, pins 13 secured to the narrow sides of the slug 9, extend outwardly through the slots 7 in the narrow side walls of the constricted waveguide portion 3. The pins 13 may be actuated in any convenient manner to adjust the longitudinal position of the slug 9 within the constricted waveguide portion 3. Another type of adjusting element, providing convenient operation, comprises a continuous cable drive 29 secured to each end of the slug and brought out through suitable guide apertures 31 in the waveguide walls to a conventional dial cable drive which includes guide pulleys 33, drive pulley 35 and an indicator 37.

As explained heretofore, wave transmission within the waveguide portions 1 will be subjected to extremely low attenuation since the cut-off frequency of this portion of the guide is below that of the microwave energy to be transmitted therein. The cut-off frequency of the constricted portion 3 of the waveguide is higher than that of the transmitted energy when the constricted guide portion includes an air dielectric. However, when the high dielectric constant material 9 occupies the constricted waveguide portion 3, the cut-off frequency of the constricted guide portion is lowered to a value below the frequency of the transmitted microwave energy. The resultant attenuation of the constricted waveguide portion 3 therefore will be proportional to the relative lengths of the constricted waveguide portion having an air dielectric and the portion of the constricted waveguide having a high dielectric constant material therein. It will be seen that the attenuation of the constricted waveguide portion may be varied from a very low value when the entire constricted waveguide includes high dielectric constant material to a relatively high value when the high dielectric constant material is substantially removed from the constricted waveguide portion. The maximum attenuation obtainable will depend upon the cross-sectional and longitudinal dimensions of the constricted waveguide. For example, an attenuation of 10 db. per centimeter along the longitudinal waveguide axis is obtainable in a constricted waveguide having a length along the magnetic axis of the order of eight-tenths the cut-off length at an operating wavelength of 3 cm. The attenuation may be varied readily from 5 to 20 db./cm. along the longitudinal axis by suitably proportioning the cross-sectional dimensions of the constricted waveguide portion. Another example indicates that an attenuation of 10 db./cm. may be obtained at wavelengths of 10 cm., when the length along the magnetic axis is six-tenths the cut-off length.

Figure 3 is a modification of the device described in Figure 1 wherein only the narrow side faces 4, defining the limits of the magnetic axis of the waveguide, are constricted. The pins 13 extend through slots 8 in the oppositely disposed wide faces of the constricted portion 3 of the waveguide. With this arrangement, only the narrow side faces of the waveguide 1 will be tapered to the constricted narrow faces 4 of the waveguide by means of tapered portions 5. The operation of the devices of Figures 1 and 3 will be substantially identical, since the length of the electrical axis of the waveguide does not affect substantially the cut-off frequency. The modification shown in Figure 3 is preferable mechanically to that disclosed in Figure 1 for the reason that the upper and lower faces of the high dielectric

constant slug 9 are in continuous contact with the inner surfaces of either the constricted or main waveguide wide face portions. However, the energy leakage through the slots in the device of Fig. 3 is greater than the leakage through the slots of the device of Fig. 1, since in Fig. 3 the slots are at the region of the strongest electric field.

Referring to Figures 4 and 5, only the narrow side faces 4 of the waveguide 1 are tapered, as in the device described in Figure 3. The constricted portion 3 of the waveguide includes two inclined partitions 6, 6' of low-loss insulating material which close off the ends of the constricted guide portion to provide a substantially liquid-tight compartment 10. The upper face of the constricted waveguide portion 3 includes a vent 12, while the lower face of the liquid-tight compartment 10 includes an outlet 14 to which is connected one end of a U-shaped liquid reservoir 15. A piston 17, actuated by a piston shaft 19 and a control knob 21 which extend outside of the remaining end of the U-shaped reservoir 15, provide hydraulic means for raising or lowering the level 23 of a liquid low-loss dielectric 25 within the liquid-tight chamber 10.

As the control knob 21 is moved toward the end of the U-shaped reservoir 15, the piston 17 forces additional liquid dielectric 25 into the chamber 10, which lowers the cut-off frequency of the constricted waveguide portion 3. When the chamber 10 is substantially filled with liquid dielectric, the attenuation of the constricted waveguide portion 3 reaches a minimum value, while as the level 23 of the liquid dielectric 25 is lowered in the chamber 10 the attenuation is increased to a value dependent upon the cross-sectional and longitudinal dimensions of the constricted waveguide portion. The insulating partitions 6, 6' may be inclined with respect to the longitudinal axis of the waveguide as much as required to reduce wave reflections in the main waveguide 1 from the insulating partition walls. The smaller the angle formed between the insulating partitions 6, 6' and the upper and lower waveguide faces, the lower will be the standing wave ratio in the waveguide 1.

More uniform variation of attenuation may be obtained if the waveguide and the constricted portion thereof were rotated 90°, and the outlet port 14 and vent 12 were located in opposite narrow guide faces, instead of as illustrated in Figure 5. With this arrangement the width of the constricted waveguide would be varied along the magnetic axis instead of along the electric axis as in the device of Fig. 5.

Figure 6 is another modification of the invention wherein the constricted waveguide portion 3 is U-shape to provide a suitable open-ended chamber for the liquid dielectric. The main waveguide 1 may be tapered in any manner described heretofore, and the elbows 27 of the constricted waveguide portion 3 preferably should be well rounded or shaped to minimize reflections to the main waveguide 1. In this embodiment of the invention, the vent 12 in the waveguide face 3 is not required, since venting is obtained directly into the main waveguide 1. The aperture 14 in the lower face of the U-shape constricted waveguide 3 opens into a liquid reservoir 15 having a piston 17 disposed therein. The piston 17 may be actuated by a piston shaft 19 and control knob 21 as described heretofore in Figures 4 and 5. The fluid reservoir 15 may be constructed as a U tube of the type described in

Figure 4 or it may be in any other convenient form. As the control knob 21 and control shaft 19 are moved toward the end of the fluid reservoir 15, the piston 17 forces the fluid dielectric 25 into both arms of the U-shape constricted waveguide portion 3. It will be seen that as more fluid is forced into the U-shape constricted waveguide portion 3, the length of the constricted waveguide portion which includes a high-constant dielectric is increased with respect to the length of the constricted waveguide portion which includes an air dielectric. Preferably, the fluid should not be permitted to drop below the top of the horizontal portion of the U-shape constricted portion of the guide, thereby minimizing non-linearity in attenuation adjustment, and simplifying the guiding of the resistive material 29 floated on the liquid surfaces, as described hereinafter.

In order to minimize wave reflections from the surfaces of the fluid 25 within the U-shape constricted waveguide portion 3, suitable resistive material 29 such as, for example, conductive rubber or some moderately high resistive liquid, may be floated upon the surfaces of the low-loss high dielectric constant liquid 25. The impedance of the resistive elements 29 should be calculated to minimize the reflection of microwave energy as it passes between the air-filled and dielectric-filled portions of the constricted waveguide.

Thus the invention described comprises several modifications of a device wherein the normally high attenuation of a constricted waveguide portion is adjusted by introducing therein high-dielectric-constant materials which lower the attenuation of the guide portion enclosing said materials.

I claim as my invention:

1. A variable microwave attenuator including a waveguide transmission system having a constricted portion thereof providing a region of relatively high attenuation at the operating microwave frequency and mode of wave propagation with a low dielectric constant dielectric material in said constricted portion, a relatively high-constant liquid dielectric occupying a predetermined portion of said constricted portion, and means for adjusting the dimensions of said portion and said predetermined portion.

2. A variable microwave attenuator including a waveguide transmission system of rectangular cross-section having a portion constricted along only one of the transverse axes thereof providing a region of relatively high attenuation at the operating microwave frequency and mode of wave propagation with a low dielectric constant dielectric material in said constricted portion, a relatively high-constant dielectric occupying the entire cross-section and a predetermined portion of the longitudinal dimensions of said constricted portion thereby providing a relatively low attenuation region along said predetermined longitudinal portion and a relatively high attenuation region along the remainder of said constricted portion, and means for adjusting the length of said low attenuation region.

3. Apparatus of the type described in claim 2 characterized in that said high-constant dielectric is a liquid.

4. Apparatus of the type described in claim 1 including a reservoir for said liquid, and means for controlling the volume of said liquid transferred from said reservoir to said predetermined portion of said waveguide.

5. A variable microwave attenuator including a waveguide transmission system having a U-shape constricted portion thereof providing a region of relatively high attenuation at the operating microwave frequency and mode of wave propagation with a low constant dielectric material in said constricted portion, a relatively high-constant liquid dielectric occupying a predetermined portion of said constricted portion thereby providing a relatively low attenuation region along said predetermined portion and a relatively high attenuation region along the remainder of said constricted portion, a reservoir for said liquid dielectric, a port interconnecting said constricted portion and said reservoir, and means for controlling the volume of liquid transferred from said reservoir to said constricted portion for adjusting the relative lengths of said high and said low attenuation regions.

6. A variable microwave attenuator including a waveguide transmission system of rectangular cross-section having a portion constricted along only one of the transverse axes thereof providing a region of relatively high attenuation at the operating microwave frequency and mode of wave propagation with a low dielectric constant dielectric material in said constricted portion, a relatively high-constant dielectric occupying a predetermined portion of said constricted portion, and means operable externally of said waveguide for adjusting the dimensions of said predetermined portion.

7. A variable microwave attenuator including a waveguide transmission system of rectangular cross section having a portion constricted along only the magnetic transverse axis thereof providing a region of relatively high attenuation at the operating microwave frequency and mode of wave propagation with a low dielectric constant dielectric material in said constricted portion, a block of relatively high-constant dielectric material tapered at both ends to minimize wave reflections therefrom and occupying the entire cross-section and a predetermined portion of the longitudinal dimensions of said constricted portion thereby providing a relatively low attenuation region along said predetermined longitudinal portion and a relatively high attenuation region along the remainder of said constricted portion, and means for moving said block longitudinally in said constricted waveguide portion for adjusting the relative lengths of said high and said low attenuation regions.

8. Apparatus of the type described in claim 5 including impedance matching means floated upon the surfaces of said liquid dielectric within said constricted waveguide portion for minimizing wave reflections from said surfaces.

9. Apparatus of the type described in claim 1 including tapered confining means enclosing said liquid within said constricted wave-guide portion for minimizing wave reflections from said liquid.
